UNITED STATES PATENT OFFICE.

CHARLES E. GODLEY, OF DETROIT, MICHIGAN, ASSIGNOR TO EDMUND & JONES CORPORATION, OF DETROIT, MICHIGAN, A CORPORATION OF NEW YORK.

REFLECTOR.

Application filed May 8, 1922. Serial No. 559,204.

This invention relates to the construction of the reflectors of projecting lamps, especially the headlamps of motor vehicles, and its object is to so divide the reflector 5 into sections that the rays of light will be projected upon a clearly defined limited area, and in part concentrated upon a restricted portion of such area.

Lamp builders have long sought to provide headlights for vehicles which would give an even illumination of the roadway from immediately in front of the vehicle to a point in advance thereof sufficiently distant to permit the driver to see and avoid 10 all obstructions, and furthermore, to attain this object with the least expenditure of electric current. Lamps equipped with the well known parabolic reflectors cannot produce this effect as the illumination of the 15 roadway at a given distance from the vehicle is either very restricted or is much fainter than the roadway nearer the vehicle. When such lamps are so positioned that the concentrated light properly illuminates the 20 roadway sufficiently far in advance to permit the driver to avoid obstructions, the roadway nearer the vehicle is left dark. Or if the light bulb is so positioned that the 25 roadway sufficiently far in advance to permit the driver to avoid obstructions, the roadway nearer the vehicle is left dark. Or if the light bulb is so positioned that the projected rays illuminate the roadway near 30 the vehicle, too much light is projected upward and sidewise where it is liable to blind drivers of other vehicles and pedestrians.

My present invention aims to overcome these objections while still employing a 35 simple reflector of a substantially parabolic type, by deforming the reflector so that different portions thereof will project beams whose cross-sections are similar in shape but different in size, so that the larger beam 40 will afford a general road illumination of considerable spread while the more concentrated beam will afford a driving beam which will light a narrower stretch of road for a considerable distance ahead of the vehicle. Furthermore, my invention consists 45 in deforming a substantially parabolic reflector so that it will project beams of greater width than height. It also consists in providing a reflector of this character 50 which can be manufactured at approximately the same cost as an ordinary paraboloidal reflector and in which the special

deformations will not interfere with the usual machine polishing of the reflecting surface. Moreover, it consists in providing 55 a reflector construction which will be equally suitable for considerable variations both in the spread of the beams and in their relative intensity, and also adapted to be used for substantially all purposes where it is 60 desirable to project beams of relatively different transverse diameters.

In accomplishing these purposes, I employ a reflector of a generally paraboloidal form and subdivide this reflector into a plurality 65 of panels which extend transversely of the directions in which the beam is to be expanded, each of these panels having its longitudinal medial portion disposed forwardly of the general paraboloidal form of 70 the reflector farther than its lateral edges. I vary the depth or the convexity of the cross-section or the width of the panels according to the desired spread of the projected beam, and vary the relation of the central lines 75 of the panels to the vertical plane passing through the axis of the reflector according to the directions in which the beam is to be expanded. The cross section of any panel on a line radial to the inner edge of said 80 panel is the same as a horizontal cross section of the same width of the determining reflector, the center of this cross section of the determining reflector being in a line passing through the focal center of both reflectors and through substantially the middle 85 of said cross section of said panel, but reversed. This rule holds with reflectors having panels, all of whose sides are parallel and vertical and with reflectors divided into 90 panels of irregular form so long as the cross sections of these panels are tilted into the planes in which the light is to be spread. For example, if the central lines of the panels in a headlight reflector having a horizontal axis were all in vertical planes, the beam of the reflector would be expanded from circular to elliptical cross-sections with the major axis of the ellipses horizontal. If such generally upright panels 100 all curve slightly toward or away from a vertical plane, the beam will be changed in cross-section substantially to that of a horizontal rectangle.

While such alterations in beam sections can be accomplished by means of panels of varying transverse sections, I prefer to convex each panel forwardly in the relative transverse sections of a parabola of slightly longer focus than the normal parabolic reflector for the greater distribution, and transverse sections of a parabola of a much longer focus for the more concentrated light. By using the longer-focus transverse sections, the panels can all be of the same width or any predetermined width, the spread of light being determined by the focal length of the parabola used in determining the transverse sections of the panels.

By using transverse parabolic sections in the panels I find that the light rays reflected from each panel diverge equally from the axis of the reflector, the rays from each panel covering substantially the anticipated field of light of the different sections.

I have also found that if the convexity of each panel is just the reverse of the normal parabolic section for the same portion of the reflector, using narrower panels for greater concentration and wider panels for the more diffused light, that the width of panels are determined by the width of spread desired in the projected fields.

In the accompanying drawings Fig. 1 is a horizontal section of a reflector embodying the present invention on the line 1—1 of Fig. 2. Figs. 1^a, 2^a, 1^b and 2^b are diagrams showing the process for determining the proper cross sections of the paraboloidal panels. Fig. 2 is a front elevation of the reflector. Fig. 3 is a diagram illustrating the effect of the light rays projected by the reflector shown in Figs. 1 and 2. Figs. 4, 5 and 6 are views corresponding to Figs. 1, 2 and 3 respectively of a modified form of reflector. Fig. 7 is a view of another modified form of reflector. Fig. 8 is a section on the line 8—8 of Fig. 7. Fig. 9 is a diagram illustrating the effect of the light rays projected by the reflector shown in Fig. 8. Figs. 10 and 11 are respectively elevation and vertical section of another modified form of reflector.

Similar reference characters refer to like parts throughout the several views.

In Figs. 1, 2 and 3, Fig. 2 is a front elevation of a reflector embodying this invention, but Figs. 1 and 3 are to be taken together, the observer being supposed to stand at the bottom line of the drawing and look at the diagram Fig. 3 which, being a vertical plane receives the rays of light from the reflector 1.

The reflector 1 is generally parabolic in form. If a light bulb could be made with a filament with substantially no dimensions and this filament mounted at the focus of the reflector, then this reflector, if a perfect parabola, would project a beam of light of

the diameter of the reflector. The filaments of light bulbs are, however, of considerable size so that the light projected is in the form of a cone whose surface is somewhat indefinite.

After the parabola has been formed and polished, it is placed between proper dies and its surface is deformed so as to be divided into panels 3 and 4, those next the central aperture 2 of the reflector in Figs. 1 and 2 being wider than those farther away. Each of these panels is substantially in a vertical plane, as shown in Fig. 2, those on each side of the center of the reflector being parallel to each other, but all of the panels are bowed slightly with respect to that plane in order to effect the projection of added diffused light toward the corners of the main projected field.

The desired width of the panels being fixed, the exact cross sections of the panels may be determined after the manner shown in Figs. 1^a to 2^b inclusive. For any given portion of the panel E shown in Fig. 2^a, I first determine the center G of the cross-section of the corresponding part of the original or true paraboloidal surface 1, as shown in Fig. 1^a. I then draw a line from this point G to the focus F of the true parabolic surface portion and also plot the corresponding portion of a determining parabola P. The focal length of the reflector 1 is indicated by the line B and that of the parabola P by the line C. The point H at which the focal line F G intersects the determining parabola P indicates the central point of a small section of the parabola P' which has the proper curvature for the desired panel cross-section. If this determining parabola is of greater focal length than the parabola 1 (which is part of the true paraboloidal surface from which the reflector is to be formed and which it will still approach rather closely when finished) this curvature is reversed as shown in Figs. 1^a and 1^b.

Cross-sections of the panel 3 at other points are similarly determined, each being taken radially to the inner edge of the panel as shown by the lines K in Fig. 2^a. This insures a panel which effects an unusually uniform distribution of light. Owing to the resulting uniform density of the projected beam and of the beam-widening effect due to the edgewise curving of the panels, they cooperate in projecting a beam of approximately rectangular cross-section with its upper and lower borders substantially parallel to the plane of the line E in Fig. 2^a. The lines K indicate how the rays of light are deflected up and down so as to proceed along lines substantially at right angles to the border lines of the panels at the points of reflection.

Where the panels are at any other angle to the vertical plane of the reflector or

parallel thereto, the same process for determining the curvature of the panels composing the reflector may be followed, as indicated in Figs. 1^b and 2^b. This is true no matter at what angle the line E, (Fig. 2^b) crosses the side edges of the panels.

Each of the panels presents a transversely convex surface toward the plane of the open end of the reflector and the curvature of each panel at every point in its length is desirably the same as a horizontal cross-section of the determining reflector taken in a line passing through the focal points of both reflectors, reversed and placed so as to coincide with the normal parabolic reflector surface at the edges of each panel and tilted into the planes in which the light is to be spread. The curvature of each panel is therefore greatest at the line 1-1 of Fig. 2, which is the horizontal diameter of the reflector.

Fig. 3 is a diagram A showing the proportionate illumination of a field by means of a reflector of this character, the field being divided as shown into eighty squares, and the length of the sides of the squares equalling approximately one degree of arc on a spherical surface whose radius is one hundred feet, the general focus of the reflector being at the center of this spherical surface. With the source of illumination at the focal point 9, Fig. 1, some of the reflected light rays are projected by each of the wide and deeply curved panels 3 over a surface extending from one vertical line 8 to the other, and from horizontal line 4, and if the panels 4 were coated with a non-reflecting material, it would be observed that the illumination of this area is remarkably uniform. Its side borders are not as clearly defined as its upper and lower limits but are still clearly distinguishable. This illumination is indicated by the lines 6 and 12.

The side panels 4 are narrower than the middle panels 3 and their transverse curvatures are much less so that the light reflected by these side panels is diffused to a much less extent, both horizontally and vertically, as indicated by the lines 9 and 10, for the reason that the narrower panels approach more closely to the true paraboloidal reflector surface. For example, I have found that with the panels proportioned as in Fig. 2, each of these side panels will project light on about the middle one-fourth of the field illuminated by rays projected by panels 3. The result is that at any desired testing distance, the field or chart shown in Fig. 3 can be illuminated by any combination of beams of light, that is, more or less concentration or more or less diffused light, to the extent of spreading the beam-candle-power of the normal parabolic reflector over the respective field areas. This is accomplished by varying the proportionate width of the sec-

tions or panels for the different fields of light. It is not my intention to limit myself to only two beams of light, one within the other, as it may be advantageous to throw more light onto some other point on the roadway which can easily be accomplished by altering the panels and sections so as to project two or more separate beams of light. Also it is not my intention to limit myself to the extent that the tops of the separate beams of light shall coincide at any particular distance, as it may be desirable at some time to have them coincide at a less or greater distance from the reflector, so the angle of the axes of the two or more sections of the panels may vary in degree.

It will be observed in Fig. 3, that the upper edge of the area of intense illumination caused by the panels 4 is between the horizontal line 0 and the line 1 above, which is above the upper edge of the illumination caused by the panels 3. This is produced by tilting that portion of the reflector which embodies the panels 3 on the focal axis of the reflector as a center, as indicated in Figs. 8 and 9, through an angle sufficient to make these upper beam edges differ, which in this instance means an angle of about one degree. This causes the point of most intense illumination of the field shown in Fig. 3 to be just below the horizontal line 1 instead of having the intensified field central of the less brightly lighted field.

Figs. 4, 5 and 6 show a reflector 13 having narrow panels 18 near the central opening 2 and wider panels 20 on the outside thereof. The rays reflected by the narrower panels 18 are concentrated on the space between the lines 16, the lines of reflection being indicated by the lines 16 and 17. It will be apparent that in this case, as in that shown in Figs. 1, 2 and 3, the wider panels diffuse the light over the entire area of illumination of the diagram A of Fig. 6 between the lines 14, the lines of reflection being indicated by the lines 14 and 15. But because of the shallower curvatures of the narrow panels 18, the illumination is more closely confined to the space between the lines 16 than in the reflector shown in Fig. 2, wherein the wider central panels, because of their greater curvature, diffuse the light laterally beyond the lines 6 to a considerable extent.

The area diagram A in Fig. 9 is the same as in Figs. 3 and 6 and the indications of degree of illumination are the same. The scorings of the reflector 13 are the same as shown in Figs. 4 and 5 except that the widths of the wider side panels 20 increase gradually outward. The angle between the focal axis 23 of the outer two sections comprising the wider panels 20 and the focal axis 24 of the two inner sections comprising the narrower panels 18 is only about one degree although this may be varied as desired. The

angle between the focal axis 23 and 24 may, however, vary in parabolas of different focal lengths.

Where an automobile headlight is less than four feet from the roadway and the rays 25 (Figs. 8 and 9) strike on the roadway about two hundred feet from the vehicle, the width of the area of greatest illumination, as indicated in the diagram 10 A, is usually that of the roadway and may be said to extend about one hundred feet toward the vehicle. The area of less illumination indicated as being below the line 2 of the diagram extends over practically 15 the one hundred feet of roadway next in front of the vehicle.

I have found that in reshaping a reflector to alter the cross-section of the resulting beam, the panels need not curve 20 toward each other at their ends, as shown in Figs. 1 to 8, but may curve away from each other as do the panels 28 and 29 in the reflector 30 shown in Figs. 10 and 11.

In all of these modifications the light 25 will be diffused laterally upwardly and downwardly into the planes of the tilted cross-sections of the panels, having a tendency toward squaring the corners.

From the above described illustrations it 30 will be obvious that the various features of my invention may be carried out in many different embodiments, and that the construction of reflectors according to my invention may differ widely to produce the 35 desired reshaping of the normal beams from those produced by the general type of reflector employed, according to the desired extent of the intensifying or plural beam effect and according to the relative desired 40 position of the different beams. I therefore do not wish to be limited to the particular details of construction and arrangement here disclosed, which obviously might be varied in a great many ways without departing from the spirit of my many-sided 45 invention. Neither do I wish to be limited to the use of such reflectors for vehicle headlights, as they might be employed with equal 50 advantage for other purposes, such as show window lights and so-called flood lights.

I claim:

1. A paraboloidal reflector composed of 55 a group of panels on each side of the center of the reflector, the panels having parallel sides and the panels of each group being parallel to each other, each panel being transversely convex toward the general focus of the reflector and its transverse curvature at each point being the same as that of the general curve of a parabola at that 60 point but in the opposite direction, the adjacent edges of the two inner panels of the two groups being curved apart at the center of the reflector.

2. A paraboloidal reflector composed of 65 a group of panels on each side of the center of the reflector, the panels having parallel sides and the panels of each group being parallel to each other, each panel being transversely convex toward the general focus of the reflector and its transverse curvature at each point being the same as that of the general curve of a parabola at that 70 point but in the opposite direction, the adjacent edges of the two inner panels of the two groups being curved apart at the center of the reflector, the panels of each group constituting inner and outer sections, and the panels of one section being wider than the other and adapted to produce a greater 75 diffusion of light.

3. A paraboloidal reflector composed of 80 a group of panels on each side of the center of the reflector, the panels having parallel sides and the panels of each group being parallel to each other, each panel being transversely convex toward the general focus of the reflector and its transverse curvature at each point being the same as that of the general curve of a parabola at that 85 point but in the opposite direction, the adjacent edges of the two inner panels of the two groups being curved apart at the center of the reflector, the panels of each group constituting inner and outer sections and the general focal axis of the inner sections being at an angle to the general focal axis 90 of the outer sections.

4. A paraboloidal reflector composed of 95 a group of panels on each side of the center of the reflector, the panels having parallel sides and the panels of each group being parallel to each other, each panel being transversely convex toward the general focus of the reflector and its transverse 100 curvature at each point being the same as that of the general curve of a parabola at that point but in the opposite direction, the adjacent edges of the two inner panels of the two groups being curved apart at the center of the reflector, the panels of each group constituting inner and outer sections and the general focal axis of the inner sections being at an angle to the general focal axis 105 of the outer sections, both focal axes 110 being in the same vertical plane.

5. A paraboloidal reflector whose reflecting surface is scored to form panels which are all convex toward the general focus of the reflector, the transverse curvature of 115 each portion of each panel being the same as that of the general curve of a parabola at that point but in the opposite direction.

6. A paraboloidal reflector composed of 120 panels which are all transversely convex toward the general focus of the reflector, the general surface of the panels adjacent the vertical focal plane of the reflector having 125

a focal axis at an angle to the focal axis of the general surface of the remainder of the panels.

7. A substantially parabolic reflector composed of panels of different widths, all extending in the general direction of a vertical meridional plane and all having their longitudinal medial portions disposed forwardly of the true parabolic surface, the ends of 10 the said panels all being bowed relative to the said plane, the wider panels having their focal axis at an angle to that of the narrower panels.

8. A concentrating reflector housing a 15 source of light and having the reflector portion adjacent to one central plane of the reflector formed for projecting a beam of light flattened transversely of the said plane to a substantially rectangular cross-section, the 20 reflector portions lateral of the aforesaid portion being formed for projecting a similarly flattened beam of different cross-section, the two reflector portions being relatively tilted to cause a flat side of one beam to 25 coincide substantially with the flat side of the other beam.

9. A light concentrating reflector having a horizontal axis and having its reflecting surface scored to form panels which are all 30 convex toward the general focus of the reflector, the transverse curvature of each portion of each panel being the same as that of the curve of a determining parabola having the same focal point and focal axis on 35 the determining parabola at the intersection therewith of a line from said focus passing through said portion of the panel, but reversed.

10. A light concentrating reflector having 40 a horizontal axis and having its vertically medial portion tilted so that its axis diverges from the axis of the laterally outward portions of the reflector, the lines of junction of the said medial section with the reflector portions lateral thereof being bowed 45

towards the vertical medial plane of the reflector, each of the laterally outward portions comprising panels extending from edge to edge of the reflector.

11. A light concentrating reflector having 50 a horizontal axis and having its vertically medial portion tilted so that its axis diverges from the axis of the laterally outward portions of the reflector, the lines of junction of the said medial section with the 55 reflector portions lateral thereof being bowed towards the vertical medial plane of the reflector, each of the laterally outward portions comprising panels extending from edge to edge of the reflector and presenting edges which appear parallel when viewed from the mouth of the reflector.

12. A light concentrating reflector having a horizontal axis and having its vertically medial portion tilted so that its axis 60 diverges from the axis of the laterally outward portions of the reflector, the lines of junction of the said medial section with the reflector portions lateral thereof being bowed towards the vertical medial plane of 65 the reflector, each of the said reflector portions comprising panels extending from edge to edge of the reflector, the panels in the medial portion of different width from those in the laterally outward portions.

13. A light concentrating reflector having a horizontal axis and having its vertically medial portion tilted so that its axis 70 diverges from the axis of the laterally outward portions of the reflector, the lines of junction of the said medial section with the reflector portions lateral thereof being bowed towards the vertical medial plane of 75 the reflector, each reflector portion comprising panels extending in the same general direction and each panel being forwardly convexed to an extent increasing from its ends to its middle.

CHARLES E. GODLEY.
